UNITED STATES PATENT OFFICE.

HENRY J. HAMANN, OF SOUTH CHICAGO, ILLINOIS.

FILM-WINDING APPARATUS.

1,192,517.

Specification of Letters Patent. Patented July 25, 1916.

Application filed September 2, 1914. Serial No. 859,748.

To all whom it may concern:

Be it known that I, HENRY J. HAMANN, a citizen of the United States, and a resident of the city of South Chicago, county of Cook, and State of Illinois, have invented 5 certain new and useful improvements in Film-Winding Apparatus, of which the following is a specification.

My invention relates to improvements in 10 film winding apparatus, such as is used in conjunction with motion picture machines, and has for its object the production of apparatus of this character which will be of improved construction and efficient in use.

Other objects will appear hereinafter.

The invention consists in the combinations and arrangements of parts hereinafter described and claimed.

The invention will be best understood by 20 reference to the accompanying drawings forming a part of this specification, and in which,

Figure 1 is a partially sectional side elevation of film winding apparatus embodying my invention, Fig. 2 is a section taken on 25 line $x-x$ of Fig. 1, the detachable ring and disk of the device being shown detached in dotted lines, Fig. 3 is a top plan view of the film magazine with the cover thereof broken 30 away to expose underlying parts, Fig. 4 is a section taken on line $y-y$ of Fig. 3, Fig. 5 is an elevation of the detachable ring and disk of the apparatus looking at the inner 35 side thereof, and Fig. 6 is an enlarged sectional detail of the film magazine.

The preferred form of construction as 40 illustrated in the drawings comprises a disk 1 which is fixed to a shaft 2 mounted in suitable bearings 3, said shaft being driven through the medium of a belt 4 which passes 45 around a channel pulley 5 fixed to said shaft. The belt 4 in the employment of the device, is driven from the projecting apparatus so as to secure proper timing for the film feed 50 as will be understood by those skilled in the art. The disk 1 is provided at one side with a central recess 6. Coöperating with the disk 1 is a second disk 7 upon one side of which is mounted a broken spring ring 8 55 which is adapted to be compressed so as to enter the recess 6 and engage with the outer wall thereof upon expansion of said ring when the same is released. In order to permit of the flexing of the ends of ring 8 during 60 expansion or contraction of the latter, only the central portion thereof is secured as

at 9 to the disk 7, the ends of said ring being free for flexing movement.

The inner or engaging end of ring 8 is provided with an outwardly extending annular flange 10 which is adapted, upon insertion of said ring into the recess 6, to engage behind an annular inwardly extending flange 11 provided at the outer edge of the outer wall of said recess, as clearly shown in Fig. 2. This arrangement serves to lock ring 8 and disk 1 against relative axial movement and hence to prevent accidental disengagement of said ring. With this construction it will be seen that disengagement 65 of said ring from disk 1 is effected only upon first contracting the ring in order to release the flange 10 from engagement with flange 11. Provided at the inner side of ring 8, adjacent the ends thereof are finger 70 pieces 12 through the medium of which said ring ends may be readily flexed inwardly in the manner above mentioned. The disk 7 is cut away at 13 in order to afford clearance for said finger pieces in the engagement 75 thereof. Projecting outwardly from the ends of ring 8 adjacent finger pieces 12 are substantially radially disposed fingers 14 which loosely engage with loops 15 provided at the outer side of disk 7. Said fingers 14 80 and loops 15 serve as guides for the ends of ring 8 in the expansion and contraction of the latter.

Arranged above the reel which is constituted by disks 1 and 7 and ring 8 is a horizontally disposed film magazine 16 the upper side of which is open and provided with a cover 17 hinged at 18. Rotatably mounted in magazine 16 is a film support 19, ball bearings 20 being interposed between said 90 film support and the bottom of said magazine to alleviate friction. Provided upon the upper side of support 19 is a central hub 21. Arranged adjacent said hub at one side thereof is a pair of guide rollers 22 supported by an arm 23 which is hinged at 24 to the peripheral wall of magazine 16 to extend inwardly therefrom, as clearly shown in Fig. 3. These rollers are arranged with their axes substantially parallel to that of the reel and when in operative position they lie between the planes of the ends of the hub so that they prevent any tendency in the film to lateral movement of the convolutions as they are withdrawn from the reel. 100

In the operation of the apparatus the roll of film is first placed upon the support 19 in

the magazine 16, the inner end of the film being passed between the guide rollers 22 in the manner shown in Fig. 3 so as to prevent pressing of the film against the hub 21 as results without the use of guide rollers as here arranged. The engagement of the film against the hub 21 in unwinding not infrequently mars the latter and results in friction and hence in hard running. With 10 the rollers 22 this contact with the hub 21 is overcome with the corresponding obviation of the objections mentioned. After passing from between the rollers 22 the film is passed over a guide roller 25 arranged adjacent the periphery of the magazine 16 and hence downwardly between guide rollers 26 provided in the bottom of said magazine to engagement with the ring 8 upon which the same is wound through rotation of shaft 2. 15 20 When the film has been fully wound upon said ring 8, the same is readily replaced into the magazine 16 by simply engaging the finger pieces 12 and pressing the same inwardly to compress or contract said ring 8 25 until the same is disengaged from the recess 6. When this is done, the ring 8 and disk 7 may be lifted to position over the magazine 16 and the film deposited onto the supporting element 19 through compression of contraction of said ring in order to release the film. In the insertion of a film into the magazine the cover 16 and arm 23 are rocked outwardly, as will be readily understood. After the ring 8 has been detached from the 35 disk 1 and before the film is dropped therefrom into the magazine, the pressure on said ring by the fingers may be released in order to permit of temporary expansion of the ring so as to frictionally engage with the 40 film surrounding said ring and thus prevent accidental displacement of the film therefrom before the same is properly positioned above the magazine.

While I have illustrated and described the 45 preferred form of construction for carrying my invention into effect, this is capable of variation and modification without departing from the spirit of the invention. I,

therefore, do not wish to be limited to the precise details of construction set forth, but 50 desire to avail myself of such variations as come within the scope of the appended claims.

Having described my invention what I claim as new and desire to secure by Letters Patent, is:

1. An apparatus of the class described comprising a magazine, a horizontally disposed film support rotatably mounted in said magazine, a central hub on the upper side of said support and a stationary guiding roller arranged adjacent said hub for cooperation with the film in unwinding, said roller having its axis substantially parallel to the axis of the reel and lying between the 65 planes of the ends of the hub, substantially as described.

2. An apparatus of the class described comprising a magazine, a horizontally disposed film support rotatably mounted in 70 said magazine, a central hub on the upper side of said support; a supporting arm hingedly connected with the outer wall of said magazine and projecting inwardly therefrom, and a guiding roller mounted on 75 said arm and positioned adjacent said hub for coöperation with the film in unwinding.

3. An apparatus of the class described comprising a magazine; a horizontally disposed film support rotatably mounted in 80 said magazine; a central hub on the upper side of said support; a supporting arm hingedly connected with the outer wall of said magazine and projecting inwardly therefrom; and a pair of guiding rollers 85 mounted on said arm and positioned adjacent said hub for coöperation with the film in unwinding, substantially as described.

In testimony whereof I have signed my 90 name to this specification in the presence of two subscribing witnesses:

HENRY J. HAMANN.

Witnesses:

JOSHUA R. H. POTTS,
B. G. RICHARDS.
